UNITED STATES PATENT OFFICE.

MARION L. PORTER, OF SILVERTON, COLORADO.

MINERAL-SEPARATOR.

1,077,297.

Patented Nov. 4, 1913.

Specification of Letters Patent. Application filed May 15, 1913. Serial No. 767,849.

To all whom it may concern:

Be it known that I, MARION L. PORTER, citizen of the United States, residing at Silverton, in the county of San Juan and State 5 of Colorado, have invented certain new and useful Improvements in Mineral-Separators, of which the following is a specification, reference being had to the accompanying drawings.

10 This invention relates to mineral separators and has for its primary object to provide a device for the rapid and economical separation of mineral slimes from silica and the coarser particles of metal contained in 15 the discharged water from quartz concentrating mills.

Another object of the invention resides in the provision of means for effectually and rapidly separating oil or acid treated mineral particles from the waste substances, and means for regulating the discharge of the mineral impregnated slime and the waste matter from the apparatus so that they will bear a definite relationship to each other.

25 The invention has for still another object the provision of simple and novel means for facilitating the precipitation of the heavier particles of metal while the lighter mineral particles are floated and rapidly discharged 30 from the machine.

Another object of the invention resides in the provision of an improved automatic float for releasing the silica and other waste substances, and an adjustable gate for varying 35 the discharge of the mineral impregnated slime.

Still another object of the invention is to produce a machine for the above purpose which is simple and durable in its construction, highly efficient and reliable in actual 40 use and may be manufactured at comparatively small cost.

With the above and other objects in view as will become apparent as the description 45 proceeds, the invention consists in certain constructions, combinations and arrangements of the parts that I shall hereinafter fully describe and claim.

For a full understanding of the invention, 50 reference is to be had to the following description, and accompanying drawings, in which—

Figure 1 is a top plan view of a mineral separator embodying the present invention; 55 Fig. 2 is a section taken on the line 2—2 of Fig. 1; Fig. 3 is a detail elevation; Fig. 4

is a vertical section illustrating a slightly modified form of the automatic releasing valve.

Referring in detail to the drawings, 5 designates the tank or hopper which may be constructed of wood or metal as desired and is preferably of inverted cone-shaped form. The upper edge of the tank wall is longitudinally extended to form a vertical annular flange 6 thereon. Within the upper end of this tank or hopper, a cylindrical housing 7 is concentrically disposed with relation to the flange 6, said housing being open at its upper and lower ends. The upper edge of 70 this housing is connected to the flange 6 by means of a plurality of radially disposed channelled bars 8.

A spirally coiled metal plate 9 has its inner end fixed to the wall of the housing 7, 75 and at its outer end is suitably secured to the flange 6 on the upper end of the tank 5. It will be noted from reference to Fig. 2 that this spiral metal plate gradually decreases in depth from its inner to its outer end. 80 The upper edge of this plate is notched to receive the channelled bars 8, and to these bars, a plurality of supporting rods 10 are secured at their upper ends by means of the nuts 11, the lower ends of said rods having 85 stirrups 12 formed thereon to receive the lower edge of the plate 9.

The flange 6 on the tank wall has secured thereto in any desired manner, a downwardly inclined outlet or discharge spout 90 13. A stop or deflecting plate 14 is fixed at its inner end to the outer convolution of the spirally coiled plate 9 and at its outer end to the flange 6 on the tank wall adjacent one side of the outlet or discharge spout 13. 95 This plate is preferably curved as shown. A regulating gate 15 is mounted upon the flange 6 of the tank wall. This gate consists of a plate curved in concentric relation to the flange 6 and provided upon its opposite ends with the extensions 16. In these extensions and the body of the plate, slots 17 are formed to receive the bolts 18 extending through openings in the flange 6. Nuts 19 are threaded upon the outer ends 105 of these bolts whereby the gate 15 may be securely clamped in its adjusted position. The lower end of the gate at opposite sides thereof is movable in the guide brackets 20 which are secured upon the inner face 110 of the flange 6.

To the lower end of the tank wall 5, the

plate or casting 21 is secured, said plate being centrally provided with an opening and a valve seating face 22 surrounding said opening. 23 designates the valve member suitably fixed to the lower end of the rod 24 which is movable in a guide bar 25 arranged within the tank 5 and fixed to the wall thereof at diametrically opposite points. This valve member is provided 10 with the inclined beveled faces 26 for engagement upon the seat 22 to close the opening in the plate or casting 21. A depending stem 27 is secured to the valve member 23 and is provided upon its lower 15 end with a spider 28. This stem extends through the opening in the plate 21. Within the lower end of the cylindrical housing 7, horizontal guide bar 29 is arranged, said bar being provided with an 20 opening to loosely receive the tubular interiorly threaded stem 30 on the lower end of a float 31, which is arranged within said housing. This stem has adjustable threaded 25 engagement with the upper end of the valve rod 24 and the float is provided with a suitable hand hold 32 whereby the same may be readily adjusted upon the upper end of the valve rod in accordance with the level of the water which it is desired to 30 maintain in the tank 5. A feed launder 33 discharges the mineral impregnated slime and water into the tank 5 between the adjacent inner convolutions of the spiral plate 9.

From the foregoing description, the operation of my improved mineral separator 35 will be clearly understood. As the mineral charged water is fed to the tank 5, a whirling motion is imparted thereto by the spirally coiled plate 9, the water traveling 40 slowly in the spiral bottomless trough which is formed by this plate and thereby giving the heavier particles of silica or metal a chance to settle upon the bottom of the tank. The lighter mineral particles which may 45 be made buoyant by treatment with oil or acid as in flotation processes now in common use, will travel around upon the surface of the water through this spiral trough and finally engage the deflecting plate 14 50 and be directed thereby outwardly through the discharge spout 13. Owing to the fact that the plate 9 is of relatively great depth at its inner end or the center of the tank, the ore impregnated solution is confined for 55 a greater length of time in a comparatively restricted space than when the solution moves into the outer portion of the spirally coiled plate. Thus at the center of the tank, the solution will be violently agitated during 60 its whirling motion and by contact with the deep wall of the plate 9 will thoroughly separate the light buoyant mineral particles from the heavier silica and metal. The adjustment of the gate 15 and its relation 65 to the surface of the mineral bearing fluid

determines the quantity of light metal particles which are discharged through the outlet. It is of course understood that as the depth of the mineral bearing water in the tank gradually increases and the float 31 70 is elevated thereby, the valve 23 will be opened so that the heavier particles of silica and other waste substances which have settled to the bottom of the tank will be discharged therefrom. This continued discharge of the waste products also facilitates their precipitation in the tank, as the outflow acts to draw the same downwardly to the waste valve.

In Fig. 4 of the drawings, I have illustrated a slightly modified form of the invention wherein the float 31' is mounted upon the inner end of a lever 34 fulcrumed upon the wall of the tank or hopper as indicated at 35. 36 designates the waste discharge pipe connected to the bottom of the tank and a gate valve 37 is arranged in said pipe. The outer end of the lever 34 projects beyond the wall of the tank and to the same the upper end of a rod 38 is pivotally connected. The lower end of this rod is connected to an arm 39 which actuates the gate of the valve 37. The arm 39 may be of any desired length so as to effect a quick or slow opening movement of the valve gate as may be desired.

From the above, it will be seen that I have produced a mineral separating apparatus which while simple in its construction, will rapidly and effectively separate the 100 light particles of mineral from the heavier baser materials which may be present in the slime and water. By providing the adjustable outlet gate, and the automatically operated waste discharge valve, the overflow 105 from the tank which carries the light mineral particles and the discharge of the waste matter can be so regulated as to bear a definite relationship to each other and after proper adjustment will require little or no 110 attention on the part of the operator.

By means of my invention, a very clean separation of the floating particles of metal from the waste products may be made with comparatively no expense other than that 115 incident to the initial cost of the apparatus. The invention may be advantageously employed for separating metal slimes contained in quartz mill tailings from the silica and other waste products carried thereby and is 120 of especial value in the separation of particles of metal which have been coated with acid or oil, from the silica and other undesirable waste substances which may be associated therewith.

It will be appreciated that owing to the very simple construction of the apparatus, the same can be produced at small manufacturing cost and may be kept in thorough repair at practically no additional expense. 130

The apparatus is also highly durable and efficient in practical use.

While I have above described the preferred form and construction of the several elements employed, it will be obvious that the invention is susceptible of considerable modification therein without departing from the essential features or sacrificing any of the advantages of the same.

10 Having thus described the invention, what is claimed is:

1. In a mineral separator, a tank provided with an outlet at its upper edge, radially disposed supporting bars fixed at their outer 15 ends to the wall of said tank, a spirally wound plate arranged in said tank, stirrup members depending from said bars and engaging the lower edge of said plate to support the same, and a deflecting plate fixed 20 to said spiral plate and to the wall of the tank to direct the mineral bearing water through the outlet of said tank.

2. In a mineral separator, a tank provided with an outlet spout at its upper edge, a 25 spirally wound directing plate arranged in the top of the tank and gradually decreasing in depth from the center of the tank out-

wardly to the wall thereof, said plate directing the mineral bearing water through a circuitous path from the point of intake to said 30 outlet thereby permitting the heavier particles to settle to the bottom of the tank.

3. In a mineral separator, a tank to receive the mineral bearing water, a housing centrally arranged in the upper end of said 35 tank, supporting bars connected to the housing and to the tank wall, means depending from said bars to cause the mineral bearing water to travel in a spiral path as it is fed to the tank, said tank having an outlet at its 40 upper end for the finer particles of mineral carried upon the surface of the water and an outlet at its bottom for the waste products, a valve normally closing said latter outlet, a float arranged in said housing, and a rod 45 connecting said float to the valve, to move the latter to its open position.

In testimony whereof I hereunto affix my signature in the presence of two witnesses.
